UNITED STATES PATENT OFFICE.

JAMES E. LEACH, OF LAWTON, OKLAHOMA.

DESIGN FOR A DOOR STOP AND FASTENER.

52,825.

Specification for Design.

Patented Dec. 31, 1918.

Application filed August 25, 1916. Serial No. 116,942. Term of patent 14 years.

To all whom it may concern:

Be it known that I, JAMES E. LEACH, a citizen of the United States, residing at Lawton, in the county of Comanche and State of Oklahoma, have invented a new, original, and ornamental Design for Door Stops and Fasteners, of which the following is a specification, reference being had to the accompanying drawing, forming part thereof.

The figure is a perspective view of the door stop and fastener, showing my new design.

I claim:

The ornamental design for a door stop and fastener, as shown.

JAMES E. LEACH.

Witnesses:

E. P. McMAHON,
J. S. COOTER.
